Primary Examiner — Mitchell I. Siegel*(74) Attorney, Agent, or Firm* — Whitmyer IP Group LLC(57) **CLAIM**

The ornamental design for a golf ball swing, as shown and described.

DESCRIPTION

FIG. 1 is a front isometric view of a golf ball swing in accordance with the new design;

FIG. 2 is a front elevational view thereof with a seat insert removed;

FIG. 3 is a rear elevational view thereof with a seat insert removed;

FIG. 4 is a right side elevational view thereof with a seat insert removed;

FIG. 5 is a left side elevational view thereof with a seat insert removed;

FIG. 6 is a top plan view thereof with a seat insert removed; and,

FIG. 7 is a bottom plan view thereof.

The broken lines shown in the drawings illustrate portions of the article that form no part of the claimed design.

1 Claim, 7 Drawing Sheets(56)
